United States Patent Office

Des. 188,495
Patented Aug. 2, 1960

188,495

ANTENNA

Irving Gould, Devon, Pa., assignor to Jerrold Electronics Corporation, Philadelphia, Pa., a corporation of Delaware

Filed Oct. 30, 1959, Ser. No. 58,129

Term of patent 14 years

(Cl. D26—14)

Fig. 1

Fig. 3

Fig. 2

Fig. 4

Fig. 5

Fig. 6

Figure 1 is a front elevational view of an antenna showing my new design;

Figure 2 is a rear elevational view thereof;

Figure 3 is a side elevational view thereof;

Figure 4 is an elevational view of the other side thereof;

Figure 5 is a top plan view thereof; and

Figure 6 is a bottom plan view thereof.

The dot-dash line fragmentary showing of twin-lead is for illustrative purposes only. A portion of Fig. 1 is diagonally lined to indicate a glossy surface.

I claim:

The ornamental design for an antenna, substantially as shown and described.
